UNITED STATES PATENT OFFICE.

HORACE FALK NEUMEYER, OF MACUNGIE, PENNSYLVANIA.

APPARATUS FOR TREATING OIL.

1,426,836.

Specification of Letters Patent. Patented Aug. 22, 1922.

Application filed March 1, 1918. Serial No. 219,923.

To all whom it may concern:

Be it known that I, HORACE FALK NEUMEYER, a citizen of the United States, residing at Macungie, in the county of Lehigh and State of Pennsylvania, have invented 5 certain new and useful Improvements in Apparatus for Treating Oil, of which the following is a specification.

This invention relates primarily to processes for treating oil and more specifically to a process and apparatus for treating lubricating oils with a view to separating foreign matter, such as iron particles and the like, so as to cleanse the oil of matters which 15 ordinarily prove injurious to machinery.

Another object of the invention is to provide an apparatus for treating oil in the manner above set forth which includes means for creating a magnetic field, and 20 means for flowing the oil to be treated through or in proximity to the magnetic field.

A still further object of the invention is to provide an apparatus for treating oil which 25 includes a casing having a tubular member mounted therein, a core of magnetizable material within the tubular member, a solenoid surrounding the core, and means for energizing the solenoid whereby the oil to be 30 treated may be introduced into the tube and during its passage therethrough subjected to a magnetic field for the purpose above set forth.

In addition to the foregoing my invention 35 comprehends improvements in the details of construction and arrangement of the correlative parts to be hereinafter more fully described and particularly set forth in the appended claims.

40 In the accompanying drawings in which similar and corresponding parts are designated by the same characters of reference throughout the several views in which they appear,

45 Figure 1, is a view in top plan of an oil treating machine constructed in accordance with my invention.

Figure 2, is a view thereof in vertical longitudinal section, and

50 Figure 3, is a view of the machine in horizontal section, and

Figure 4, is a detail view illustrating the essential parts in section.

With reference to the drawings, 10 indicates an oblong rectangular, casing, divided

by means of a transverse portion to define a pair of compartments 12 and 13.

Mounted within the compartment 13 is a vertical tubular member 14 terminating at its lower end in an offset spout 15 which extends through an opening 16 which is formed in one vertical end wall of the casing. The spout 15 may be formed separately of the tubular member 14 and secured thereto by solder, brazing or in any other suitable 65 manner. The upper end of the tubular member 14 projects beyond the top plate of the casing, and enters a hopper or filling member 17. Mounted within the tubular member 14 is a soft iron core 18 of a slightly 70 smaller diameter, having oppositely extending studs 19 formed integrally with its cylindrical wall to engage the inner surface of the tubular member 14 to maintain the core in spaced relation thereto, and to form an 75 annular vertical channel between said core and the tubular member. The upper end of the core 18 is formed with a vertical, internally threaded opening 20 to receive the threaded shank 21 of a deflector member, 80 said shank having a disc or valve head 22 formed upon its upper end and disposed in a horizontal plane with its periphery in closely spaced relation to the upper end of the tubular member 14 as shown in Figure 85 4. The deflector member 22 obviously extends into the hopper or filling member and when core 18 is not in its raised position, it seats on the upper end of the tube 14 to close the same. The tubular member 14 is 90 encircled exteriorly by means of a pair of spaced annular members 23 between which a coil of wire 24 is wound. Located within the compartment 12 is an electric battery 25 which may be inserted therein by forming 95 the other end wall 26 in a manner to permit the same to be moved to open or closed position, and held in closed position by means of a catch 27 of any suitable type. Mounted upon the top plate of the casing is a base 100 plate 28 having a switch arm 29 mounted thereon about a pivotal point 30. The switch arm is adapted for contact with a stationary contact 31. The contact 31 is connected to one terminal of the coil 24 while 105 the other terminal is connected to a binding post 32. The binding post 32 is connected to one pole of the battery and the other pole of the battery is connected to the switch arm 29, adjacent its pivotal connection 30. 110

In use, the oil to be treated is introduced into the hopper or filling member 17, and owing to the narrow passage defined by the closely spaced relation of the core 18 to the inner surface of the tubular member 14, the oil is forced to pass slowly through said channel. Before the introduction of the oil, the switch arm 29 is moved to closed position whereby a magnetic field is set up which is the tubular member 14 by energization of said coil and the core 18 acts as a conductor for the lines of force. The deflector plate 22 becomes magnetized and opens the tube and when oil is poured into the filling member, it first flows over said plate before entering the tube 14. The oil then flows into the tube around the core and after being acted upon by the magnetic field, it exits through the spout 15.

When used cylinder oil is treated in this manner, all metallic particles are removed therefrom as well as carbon formed by the combustion of the oil. It will be obvious that the solenoid 24 may be eliminated and the core 18 instead of being composed of soft iron may be a permanent magnet of hardened steel, thereby obviating the necessity of current supplying means.

While I have illustrated and described my invention with some degree of particularity, I realize that in practice various alterations thereover may be made, and I therefore desire to reserve the right and privilege of changing the form of the details of construction, or otherwise altering the arrangement of the correlative parts without departing from the spirit of the invention or the scope of the appended claims.

Having thus described my invention, what I claim as new and desire to secure by Letters Patent is:—

1. An apparatus for treating oil including a conduit, a core mounted therein in spaced relation, and a solenoid surrounding said conduit, to set a magnetic field within the conduit, and to magnetize said core.
2. An apparatus for treating oil including

a conduit, a filling member mounted at one end of the conduit, a core in the conduit in spaced relation thereto, a deflector plate of similar material in connection with the core and in spaced relation to one end of the conduit to insure contact of the oil with said deflector plate to force entrance into the conduit, and a solenoid surrounding the conduit to set up a magnetic field therein to magnetize the core and deflector plate.

3. An apparatus for treating oil including a casing, a tubular member vertically disposed therein, a spout terminating at the lower end of the said tubular member, a hopper mounted at the upper end of said tubular member, a core mounted in said tubular member in spaced relation thereto to define an annular channel, integrally formed studs on said core engaging the inner surface of the tubular member to retain said core in spaced relation thereto, a deflector plate, a shank formed integrally therewith, and having a threaded connection with the core, whereby the deflector plate is disposed in spaced relation to the upper end of the tubular member and is located within the hopper, a solenoid surrounding the tubular member, to set up a magnetic field therewithin to energize the core, shank and deflector plate, a battery affording a source of current located within the casing, and means for establishing or disestablishing connection between the source of current and the solenoid.

4. In a device of the class described, a tube, a hopper therefor, a solenoid surrounding said tube, a core therein, a plate carried by the core and disposed in said hopper, and normally resting upon the top of said tube to close the same and adapted to rise from its seat when the solenoid is energized.

In testimony whereof I affix my signature in presence of two witnesses.

HORACE FALK NEUMAYER.
